Inventor:
John P. Whipple
By Jno. 13, 1883
Attorney:

UNITED STATES PATENT OFFICE.

JOHN P. WHIPPLE, OF WHITEWATER, WISCONSIN.

PAINT-DISTRIBUTER.

SPECIFICATION forming part of Letters Patent No. 289,048, dated November 27, 1883.

Application filed January 22, 1883. (Model.)

To all whom it may concern:

Be it known that I, JOHN P. WHIPPLE, a citizen of the United States, residing at White-water, in the county of Walworth and State of Wisconsin, have invented certain new and useful Improvements in Paint-Distributers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in a certain paint-distributer for which Letters Patent of the United States No. 256,852 were granted to Abner Peeler on the 25th day of April, 1882.

My improvements consist, first, in the construction of the wind-wheel, by which the current of air with which it is driven is applied with more effective force; second, in the addition of a drive-wheel in connection with the wind-wheel, whereby two needles may be operated by a single current of air; third, in the manner of attaching the needles to the operating-wheels direct, whereby the several crank-arms used for such purpose, and shown in said patent, are dispensed with; fourth, in the needle provided with a flexible portion, and adapted to be so bent as to conform to the circular movement of the wheel to which it is attached without bending the needle or disturbing the position of its point; fifth, in the peculiar shape and construction of the paint-troughs, whereby they are adapted to retain paint when the distributer is operated in a vertical position; sixth, in the peculiar thin form of that portion of the needle near its eye, as adapted to render the needle at such point more flexible; seventh, in the device for adjusting the needles to the vertical air-tubes; eighth, in the peculiar form of the metallic supporting-plate by which the operative mechanism is brought below the hand-block, whereby room is provided for the fingers of the operator between said hand-block and the canvas when the operative mechanism is in position for use; ninth, in the clasp or retaining device by which the cover is secured when

closed; tenth, in the device for retaining the needles in the guide-groove.

My invention is further explained by reference to the accompanying drawings, in which—

Figure 1 is a perspective view. Fig. 2 is a top view. Fig. 3 is a detail view, and Fig. 4 represents one of the needles detached from the machine.

Like parts are represented by the same reference-letters throughout the several views.

A' is the hand-block by which the distributor is held when operated.

A is a supporting-plate of the operative mechanism. The plate A is curved downward at b, so that the operative mechanism is brought upon a lower level, for the purpose mentioned. The plate A is adapted to move on its retaining-screws d d when adjusting the needles to the air-tube, as mentioned.

B is the device by which such adjustment is made when said screws d d are sufficiently loosened to permit of the required movement. The device B consists of a screw, which is inserted in the block A', and provided with a short lug, c, operating in and against the respective sides of the vertical slot D, said screw being also provided with an arm, E, by which it is turned. The plate A is moved in either direction by moving the lever E, motion being communicated therefrom to the plate by the lug C.

The air-wheel F consists of two disks, G G, a central shaft, I, and an annular connecting-drum, J', immediately surrounding said shaft, and curved air-buckets H. The lower end of the shaft I is provided with a pinion, J, which meshes into pinion K, through which pinions motion is communicated from said wind-wheel H to said drive-wheel L. Both wheels H and L are provided with crank-pins M M, to which the needles are attached. The needle N (shown in Fig. 4) has an elongated eye, O, extending at right angles to its body, for the reception of the crank-pins M, which peculiar form of eye permits of the lateral movement of the pitman therein.

Q is the thin portion of the needle, by which it is made flexible.

P P are the paint-troughs. By my improvement in their shape they are curved upward

at R, so that they will retain the paint when the distributer is operated in a vertical position.

S is a retaining-button, which is adapted to 5 turn on plate T, whereby it is brought over the body of the needles, thereby retaining the needles in the guide-grooves W. The wheels K and L are made detachable, and may be removed and but one of the needles operated at 10 a time.

The air-tubes for operating the wind-wheel and distributing the paint, and the stop-cocks for controlling the air in such tubes, are constructed substantially as described in said patent. One additional air-discharging pipe, B', is, however, provided, to co-operate with the 15 additional needle employed. s' s' are stop-cocks in air-tubes. The air-tubes are adapted to be connected with an air-pump and receiver, from which the required air is supplied, the same as in the device shown in said patent.

Having thus described my invention, what I 20 claim as new, and desire to secure by Letters Patent, is—

1. The combination, with the wind-wheel H, of the drive-wheel L, the same being connected together by detachable gear K and gear J, as set forth.

2. The combination, with the operative 25 wheels H and L, of a distributing-needle, N,

said needle or needles being connected directly to said wheels by crank-pins M, as set forth.

3. The combination of the button S with the needle N and guide-groove W, as adapted 30 to retain said needle in said groove, as set forth.

4. The combination of the adjusting device B with the plate A and block A', substantially as and for the purpose specified. 40

5. The combination of the peculiarly-curved or angularly-shaped plate A with the block A' and operative mechanism of the device, the shape of said plate being adapted to bring the operative mechanism below the plane of 45 the block A', substantially as and for the purpose specified.

6. The needle N, having a reduced flexible upper portion, as described, whereby it is adapted to conform to the circular movement 50 of the crank-pin, substantially as and for the purpose specified.

7. The curved trough P, so shaped as to retain the paint when the device is operated vertically, in combination with the distributing- 55 needles N, as set forth.

In testimony whereof I affix my signature in presence of two witnesses.

JOHN P. WHIPPLE.
